Primary Examiner — Darlington Ly*Assistant Examiner* — D. Ryan Tisdale(74) *Attorney, Agent, or Firm* — Van Court & Aldridge LLP(57) **CLAIM**

The ornamental design for a vehicle door as shown and described.

DESCRIPTION

FIG. 1 is a right side view of a vehicle door according to the new design;

FIG. 2 is a rear view thereof;

FIG. 3 is a front view thereof;

FIG. 4 is a top view thereof;

FIG. 5 is a bottom view thereof;

FIG. 6 is a top, rear, right side perspective view thereof;

FIG. 7 is a left side view thereof; and,

FIG. 8 is a top, rear, right side perspective view shown with environment.

The broken lines illustrate portions of the vehicle door that form no part of the claimed design. The vehicle, shown in broken lines in FIG. 8, is for the purposes of showing environment and forms no part of the claimed design.

1 Claim, 8 Drawing Sheets(56)
